UNITED STATES PATENT OFFICE.

JEREMIAH W. ALBIN, OF BABYLON, NEW YORK, ASSIGNOR OF ONE-FOURTH TO DAVID CARRS RICKETTS, OF BABYLON, NEW YORK.

MUSIC-LEAF TURNER.

No. 899,933.

Specification of Letters Patent. Patented Sept. 29, 1908.

Application filed April 2, 1908. Serial No. 424,784.

To all whom it may concern:

Be it known that I, JEREMIAH WESLEY ALBIN, a citizen of the United States, and a resident of Babylon, in the county of Suffolk and State of New York, have invented a new and Improved Music-Leaf Turner, of which the following is a full, clear, and exact description.

This invention relates to certain improvements in music-leaf turners, and more particularly to that type of mechanism adapted for supporting sheet music, and having mechanism operating to successively turn the sheets.

The object of the invention is to provide a construction whereby the successive movements of an operating member serve to turn the several sheets in succession, and also serve to return all of said sheets to the original position to permit the piece to be played over again.

Reference is to be had to the accompanying drawings, forming a part of this specification, in which similar characters of reference indicate corresponding parts in all the figures, and in which

Figure 1 is a front view of a music-leaf turner embodying my invention and illustrated as applied to a piano; Fig. 2 is a vertical section on the line 2—2 of Fig. 1; Fig. 3 is a view of the reverse side of a portion of the apparatus, showing the parts in the position occupied before any of the leaves are turned; Fig. 4 is a view similar to Fig. 3, but showing the parts in the position occupied after the operating member has been moved to turn one leaf; Fig. 5 is a view similar to Figs. 3 and 4, but showing the parts in the position occupied after the operating member has turned a second leaf; Fig. 6 is a substantially horizontal section on the line 6—6 of Fig. 3; Fig. 7 is a transverse section on the line 7—7 of Fig. 6. Fig. 8 is a longitudinal section through the apparatus, taken on the line 8—8 of Fig. 2 and looking in the direction indicated by the arrow; Fig. 9 is a transverse section on approximately the line 9—9 of Fig. 6; Figs. 10, 11 and 12 are perspective views of the three slides employed; and Fig. 13 is a perspective view of one of the controlling springs.

In the specific construction illustrated in the accompanying drawings, I provide a supporting plate 10, having means connected thereto for rigidly but detachably securing

the same to a piano, means for supporting the music, the sheets or leaves of which are to be turned, and means for engaging with the several leaves for turning them as the music is played, and for returning them to their original position after the piece is played or it is desired to go back and repeat. For securing the supporting plate 10 to the piano or other musical instrument or stationary body, two arms 11 are provided, pivotally secured to the rear side of the plate adjacent its ends and adapted to engage with the upper side of the front panel A of the instrument below the cover thereof. These arms, as illustrated, are formed of rods pivotally mounted in brackets 12 and extending from the upper edge of the supporting plate 10 rearwardly to engage with the front side of the front panel A of the piano, thence upwardly to the upper edge of said panel, and thence transversely across the top of the panel. At the end of each arm there is provided a plate 13, adapted to engage with the inner side of the piano front, and a wing nut 14 rotatably mounted upon the threaded end serves to force the plate 13 into position and lock the arms rigid to the piano front. Those portions of the arms which engage with the piano, are preferably covered with a rubber tube 15 or other suitable soft material, to prevent the marring of the instrument. After the device is secured, as above described, the piano lid B is closed down upon the upper surface of the arms, so as to more effectively secure them in place. Secured to the lower edge of the supporting plate 10 are two sets of lazy tongs 16—16, connecting the supporting plate to a base 17. The latter is preferably provided with an outwardly-extending flange or projection, as indicated in Fig. 2, which serves to support the music at the lower edge thereof. The base 17 is preferably provided with braces 18 pivoted to the under side thereof and adapted to extend at substantially right angles to the general plane of the lazy-tong connections 16 and to engage with the front panel A of the piano and hold said base more firmly in position.

For turning the leaves or sheets of music, I provide a plurality of arms pivoted to the supporting plate 10, and each having means for attaching the same to a sheet or leaf at the upper edge of the latter. Any suitable number of arms may be provided, dependent upon the nature of the music or the number

of leaves or pages to be turned. For purpose of illustration, I have selected a form in which there are two leaf-turning arms 19 and 20. The plate 10 carries two brackets 21 and 22 for supporting a pivot 23, and the two arms 19 and 20 are provided with hubs 24 and 24^a respectively mounted on said pivot. The plate is cut away adjacent the pivot, and each hub is provided with a plurality of teeth forming a segment gear. These gears extend through the opening in the plate, so that they may be rotated by longitudinally-movable rack bars on the rear side of the plate. Each arm is provided with means for securing the same to a sheet of music, said means preferably comprising pairs of jaws 25 held in engagement with each other by sliding collars 26. Each arm may be provided with as many of these pairs of jaws as desired, but, as illustrated, the arm 19 is provided with jaws at its outer end and also adjacent its hub, while the arm 20 is provided with jaws only adjacent its outer end.

25 On the rear side of the plate 10, I provide a plurality of slides or bars movable longitudinally and having operative engagement with the hubs 24 and 24^a so as to rotate the latter and swing the arms. The number of slides or longitudinally-movable bars is one greater than the number of leaf-turning arms, there being provided one slide for each arm and an extra slide, by means of which the arms are returned to their original position.

30 As shown, I provide a slide 27 for the arm 19 and its hub 24, a slide 28 for the arm 20 and its hub 24^a, and a slide 29 serving to bring about the return movement of the other slides and their arms. The three slides are 35 mounted side by side in engagement with the rear surface of the plate 10 and are held in position by a guide block 30 and a bracket 31. The upper and lower ends of the guide block 30 are secured to the plate, while intermediate its ends it is cut away to receive the several slides. Intermediate the bracket 31 and the guide block 30, there is provided a second bracket 32 similar to the bracket 31, but preferably out of engagement with the 40 several slides. The brackets 31 and 32 are formed of sheet metal and have base flanges 33 extending in opposite directions adjacent the upper and lower edges of the plate 10, so as to form guides for the upper and lower 45 slides. The uppermost slide 28 is provided with a series of teeth 28^a on the side thereof toward the plate 10, which teeth are in engagement with the hub 24^a of the arm 20, and the middle slide 27 is provided with similar teeth 27^a in engagement with the hub of the arm 19. Thus, as either of these slides is moved longitudinally, the hub in engagement therewith is rotated and the arm carried by said hub is moved away from engagement with one end of the plate, through an

arc of 180 degrees into engagement with the opposite end of the plate. The slide 27 is provided not only with the teeth in engagement with the hub of the arm 19, but is also provided with a series of teeth 34 on the side 70 thereof toward the lowermost slide 29. The slide 29 is provided with teeth 35 on its upper edge and oppositely disposed to the teeth 34.

Intermediate the toothed portions of the two slides 27 and 29 and mounted within the cutaway portion of the block 30, I provide a pinion 36 in engagement with both of said rows of teeth. Thus, when either of the two slides 27 and 29 is moved longitudinally in one direction, the other of the two slides is 80 moved a corresponding distance in the reverse direction through the instrumentality of the pinion 36.

It is desired to first swing the arm 19 from the position shown in Fig. 1 over into engagement with the left-hand end of the plate 10 to turn the first sheet of the music, to then swing the arm 20 over to a position adjacent the arm 19 to turn the second sheet of music, and to then return both arms to the position 90 shown in Fig. 1, to permit the piece to be replayed. In order to lock the arm 20 and slide 28 against movement during the operation of the arm 19 and slide 27, I provide the slide 28 with a transverse groove 37, shown 95 most clearly in Figs. 5 and 10. A spring 38 is secured to the outer surface of the block 30 and is provided with a flange 39 extending along one side of the block 30 and adapted to enter said groove 37 to lock the slide 28 100 against longitudinal movement. The spring also carries a flange or projection 40, extending longitudinally of the slide 27 and adapted to engage with a cam-faced block 41 carried by said slide adjacent the end thereof. While 105 the slides are in the position shown in Figs. 1 and 3, the slide 28 is positively locked in position. When the slide 27 is moved to the position shown in Figs. 4 and 8, the cam 41 engages with the projection 40 and raises the 110 flange 39 of the spring 38 out of the groove 37. This liberates the slide 28 and permits of its movement.

To lock the slide 28 to the slide 27 so that the two slides will move together during 115 their return movement and return both arms to their original position simultaneously, the slide 27 is provided with a transverse groove 42, shown most clearly in Figs. 6 and 11. The slide 28 is provided with a cam block 43 120 serving to support a spring 44, which latter is provided with a flange or projection 45 adapted to extend into the groove 42. The spring is also provided with a flange or projection 46, adapted to engage with the lower 125 end of a cam lever 47 carried by the block 30. With the parts in the position illustrated in Fig. 3, the cam lever 47 holds the spring 44 outward and holds the projection 45 out of engagement with the groove 42. 130

The slide 27 may then be freely moved to the position shown in Figs. 4 and 8. This movement of the slide 27 liberates the slide 28 from the spring 38 and permits the slide 28 5 to be moved to the position shown in Fig. 5. As soon as it reaches this position, the flange 45 of the spring 44 enters the groove 42 and locks the slides 27 and 28 together. Now, upon the longitudinal movement of the slide 10 29, the pinion 36 is rotated and the two slides 27 and 28 are returned simultaneously. If there is but one sheet to the music, the two arms may be moved simultaneously in both directions by moving the cam lever 47 from 15 the position shown in solid lines in Figs. 3, 4 and 5, to the position indicated in dotted lines. While in the dotted position, the projection 46 of the spring cannot engage with the cam lever, so that the two slides 27 and 20 28 remain permanently locked together. The cam lever enters beneath the free end of the spring 38 and holds the flange 39 thereof permanently out of the groove 37.

In order to move the slides in the order 25 above referred to, I provide an operating member, preferably in the form of a longitudinally-movable rod 48, mounted in the brackets 31 and 32 and held substantially parallel to the slides but spaced a short distance therefrom. The rod may be moved longitudinally in any suitable manner, but, as illustrated, the rod is provided with a cord or wire 49 connected to one end thereof for moving the rod in one direction, and is 30 provided with a coil spring encircling one end and engaging with the bracket 32 for moving the rod in the opposite direction. The rod carries a finger 50 extending toward the slides, and each of the slides is provided 35 with a stop between the brackets 31 and 32 for engagement with the finger, and also a cam for moving the finger about the rod as an axis and to bring the end of the finger into engagement with the stop of another slide. 40 Each of the stops is preferably in the form of a transverse lug or ridge extending across the rear surface of the corresponding slide. The stop 51 on the slide 28 and the stop 52 on the slide 27 are in such positions in respect 45 to each other, that they are in alinement, as shown in Figs. 3 and 5, when the two arms 19 and 20 are in positions adjacent each other. Before either of the two leaf-turning arms is moved, the two stops 51 and 52 are 50 intermediate the two brackets 31 and 32, but after both of the arms have been moved to turn the two pages, the stops are both in alinement with the bracket 31. A stop 53 on the slide 29 moves through the same distance as do the two stops 51 and 52, but is also at the opposite end of the grooves from the stop 52, by reason of the pinion connections between the slides carrying these stops.

As previously stated, each of the slides 55 carries a cam block on its rear side for en-

gagement with the finger 50 and moving the latter transversely of the slides. The cam block 43 carried by the slide 28 extends from adjacent the upper edge of said slide to adjacent the lower edge of the slide 27. This cam block is movable from a point adjacent the guide block 30 through an opening in the bracket 32 to a position between the brackets 31 and 32. The rear of the block 43 opposite to the guide block 30 is inclined downwardly toward said guide block. This cam block serves the double purpose of operating upon the finger 50, and supporting the spring 44. The guide block 54 carried by the slide 27 terminates substantially flush 70 with the upper and lower edges of said slide, and its upper edge is tapered or downwardly inclined in opposite directions from a point intermediate the ends of the block. When the two arms 19 and 20 are in positions adjacent each other, the inclined edge of the block 54 is adjacent to and spaced from the edge of the block 43 a distance sufficiently great to permit the finger to pass therebetween. The cam block 55 carried by the 75 slide 29 extends from a point below the center of said slide upward to a point intermediate the edges of the central slide 27. The edge of this cam block away from the guide block 30, is inclined downwardly toward the bracket 31.

The two brackets 31 and 32 are connected together at their outer ends by a rod 56, adjacent to the operating member 48, and said operating member carries a plate 57 rigidly secured thereto, said plate having a notch in the edge thereof to receive the rod 56 and prevent the rotation of the rod 48 and its plate 57, as clearly shown in Fig. 7. The finger 50 is pivoted to the rod adjacent the plate and is movable in a plane parallel with the surface of said plate and in engagement therewith. The finger carries a spring-pressed pin 58, longitudinally movable therethrough so that the end which engages with the plate 57 may enter any one of a plurality of holes or depressions 59 in said plate. The engagement of the pin with the holes or depressions 59 serves to hold the finger in a definite position in respect to the plate, save when the finger is moved by the action of one of the cams.

The action of the operating member 48, finger 50, and the several cams and stops, may be briefly described as follows: All of the parts are in the position indicated in Fig. 3 before either of the arms 19 or 20 is moved to turn a page or leaf of the music. The finger 50 at this time is in the position shown in Fig. 7, that is, it is in the center of its three possible positions and terminates closely adjacent the slide 27. By moving the operating member longitudinally to the position indicated in Fig. 4, the slide 27 is moved and the leaf-turning arm 19 swung to turn a leaf 130

or page. The movement of the slide 27 causes a movement of the slide 29 in the reverse direction under the action of the pinion, while the slide 28 is locked against movement by the engagement of the spring 38 in the groove 37. Upon the return movement of the operating member, the finger engages with the cam block 54 and is moved upwardly so that its point terminates adjacent the 10 upper slide 28. Upon moving the operating member 48 longitudinally a second time, the finger engages with the stud 51 and moves the slide 28 to the position indicated in Fig. 5, which moves the cam block 43 through the 15 bracket 32. Upon the return movement of the operating member, the finger engages with the cam surface of the block 43 and is moved downwardly, so as to terminate adjacent the surface of the lower slide 29. 20 Upon moving the operating member 48 against the action of the spring a third time, the finger engages with the stud 53 and moves the reversing slide 29, which, through the action of the pinion and the locking 25 mechanism between the slides 27 and 28, causes both of said last-mentioned slides to return to their original positions. Now, upon the return movement of the operating member 48, the finger engages with the 30 surface of the cam block 55 and is moved upwardly to the original position adjacent the surface of the middle slide 27.

As previously stated, the operating member is moved longitudinally in one direction 35 by the pulling upon the cord or wire 49. The cord may be connected to any suitable mechanism for pulling the same, as, for instance, a series of pulleys and levers connecting one end to a pedal, whereby the musician 40 may operate the turner as frequently as desired without necessitating the use of the hands.

Having thus described my invention, I claim as new and desire to secure by Letters 45 Patent:

1. A music-leaf turner, comprising a plurality of leaf-turning arms, a slide operatively connected to each of said arms and movable longitudinally to swing the same, an auxiliary slide, connections whereby it serves upon 50 its longitudinal movement to return all of the first-mentioned slides and arms to their original position, and a single operating member for all of said slides.

55 2. A music-leaf turner, comprising a plurality of leaf-turning arms, slides operatively connected thereto for swinging said arms, an operating member having a finger adapted to engage with the slides to move said arms in 60 succession in one direction, and means for locking said slides together, whereby the arms will be moved simultaneously in one direction.

3. A music-leaf turner, comprising a leaf-turning arm having a hub, a slide in operative engagement with said hub for swinging said arm, a second slide, a pinion intermediate said slides and in engagement with both, an operating member and means whereby it is adapted to engage with said slides in succession for moving them longitudinally to swing said arm back and forth. 65

4. A music-leaf turner, comprising a plurality of leaf-turning arms, a slide operatively connected to each of said arms for swinging them in one direction, a reversing slide operatively connected to one of the first-mentioned slides for swinging said arms in the reverse direction, and means for locking together the first-mentioned slides while they move in one 80 direction and permitting their independent movement in the reverse direction. 75

5. A music-leaf turner, comprising a plurality of leaf-turning arms, a plurality of slides operatively connected to said arms, 85 each of said slides having a stop and a cam block, an operating member substantially parallel to said slides, and a finger carried by said operating member and adapted to engage with said stops for moving said slides 90 longitudinally, said finger being moved transversely of said slides by means of said blocks. 95

6. A music-leaf turner, comprising a plurality of leaf-turning members, members one operatively connected to each of said first-mentioned members and movable to swing the same, an auxiliary member operatively connected to return all of the first-mentioned members and all of the second-mentioned members to their original position, and a 100 single operating member for said second-mentioned members and said auxiliary member. 105

7. A music-leaf turner, comprising a plurality of leaf-turning arms, slides operatively connected thereto for swinging said arms, an 110 operating member for moving said slides to swing said arms in succession in one direction, and means whereby said operating member returns all of said slides and arms simultaneously in the reverse direction. 110

8. A music-leaf turner, comprising a plurality of leaf-turning arms, a plurality of slides operatively connected to said arms, an operating member for moving said slides longitudinally in succession to swing said arms, 115 means for locking said slides together, an auxiliary slide, and a pinion intermediate said auxiliary slide and one of said first-mentioned slides.

In testimony whereof I have signed my 120 name to this specification in the presence of two subscribing witnesses.

JEREMIAH W. ALBIN.
